UNITED STATES PATENT OFFICE

2,686,044

HEAT EXCHANGER

Pierre Edmond Jules Marie Maldague, Seraing,
Belgium, assignor to Societe Anonyme John
Cockerill, Seraing, Belgium, a Belgian company

Application October 14, 1949, Serial No. 121,347

Claims priority, application Belgium
October 16, 1948

1 Claim. (Cl. 257—224)

1

In heat exchangers with a nest of tubes the transmission of heat is effected between a stream of fluid circulating through the interior of the tubes and another stream of fluid circulating over the outside of the tubes. The tubes forming the nest of tubes are secured in a fluid-tight manner in tubular plates by means of swaging or ramming. In many applications it is indispensable that the tubes forming the nest of tubes may be replaced individually in the case of deterioration; the easy replacement of each tube individually is only possible when the axis of the tubes is at constant curvature and at constant torsion, that is to say, that from a technical point of view this axis is either straight or curved along an arc of a circle.

In these exchangers, it is also desirable for the coefficient of thermal transmission to be as high as possible so that it is possible to reduce the surface of heat transmission and consequently, the cost of the apparatus. It is also necessary to take care that the streams of fluid passing through the apparatus are subjected to the minimum possible loss in load so that the mechanical power dissipated in the apparatus is at a minimum. Finally it is desirable that irregularities in temperature of the various parts of the apparatus do not cause the appearance of considerable stresses in the metal.

Up to the present time it has not yet been possible to obtain simultaneously all the desiderata referred to above.

The present invention has for its principal object to provide a method of construction of heat exchangers with a nest of tubes which simultaneously produces a satisfactory transmission of heat, a low loss of load in connection with each of the streams of fluid, low stresses due to thermal expansions and the easy individual replacement of the tubes constituting the nest.

For the purpose of obtaining this result, the heat exchanger is essentially characterised in that the tubes forming the nest are arranged in cylindrical coaxial layers of revolution provided with two widened terminal sections and if necessary with a central straight or substantially straight central section.

Other objects and other features of the invention will appear from the detailed and purely explanatory description set out hereinafter with reference to the accompanying drawings of some forms of construction of heat exchangers according to the invention.

Figures 1 and 2 are diagrammatic illustrations of tube contours and derivation thereof. Figure 3

2

is a diagrammatic longitudinal section illustrating tube layer disposition. Figure 4 diagrammatically illustrates the arrangement of tubes in a layer. Figures 5, 6 and 7 diagrammatically illustrate an arrangement of tubes having a non-cylindrical central portion. Figure 8 is a side elevation of a heat exchanger. Figure 9 is a section taken along the line A—A of Figure 8 and Figure 10 is a section taken along the line B—B of Figure 8.

Fig. 1 shows diagrammatically the outer contour of the nest of tubes of a heat exchanger according to the present invention.

The surface, casing of the nest of tubes, is a cylindrical surface of revolution about the axis *a*, the generating line of this cylindrical surface being the line *b*. The volume in which is contained the nest of tubes consists of three separate parts: the first part, comprised between the sections 1 and 2, has a general truncated shape converging from the section 1 to the section 2; the second part, included between the sections 2 and 3, has the general shape of a straight cylinder of revolution, of constant cross-section; the third part, included between the sections 3 and 4, has a general shape converging from the section 3 to the section 4.

Fig. 2 shows a straight cylinder identical with that in Fig. 1, included between the sections 2 and 3, this cylinder being extended in Fig. 2 up to the sections 1 and 4 in Fig. 1. The section 10 is the middle section of Figs. 1 and 2.

The straight line segment *c* in Fig. 2 represents the line, in the plane of the drawing, of a semi-plane at right angles to the plane of the drawing passing through the points 5 and 6 and through the point of intersection of the axis *a* in the section 10, the intersection of this semi-plane with the cylinder of Fig. 2 being the semi-ellipse shown in Fig. 2 after folding in the plane of the drawing. The points 7', 8' and 9' of the folded semi-ellipse *d* are folds at the respective piercing points 7, 8 and 9 of the semi-ellipse in the respective sections 2, 10 and 3. The curve *e* in Fig. 2 indicates an arc of a circle of correct size, defined by the three points 7', 8' and 9', and limited at 11' and 12'. The segment *c* of Fig. 2 also represents the projection, in the plane of the drawing, of the arc of circle *e* brought into the secant plane of the line *c*. The rotation, about the axis *a* of the arc of circle *e*, placed in this latter position, generates the cylindrical surface shown in Fig. 1 and defines, with precision, the generating line *b*, the section thus obtained from the generating line *b*, 55 comprised between the sections 2 and 3, being

generally approximately and not rigorously a straight line. From a sectional point of view, this latter approximation is without practical importance, as the difference between a straight cylinder and the actual cylinder comprised between the sections 2 and 3, is comprised within the tolerance of manufacture. When a predetermined tolerance is adopted for the dimensions of a true cylinder between the sections 2 and 3, it is possible to take this tolerance into consideration in drawing the arc of circle e , so that this is not defined rigorously by the points 7', 8', and 9' but may deviate therefrom within limits defined by the admitted tolerances.

The method of generation of the surface shown in Fig. 1, by the rotation of an arc of circle about an axis, constitutes the principle of construction of heat exchangers with a nest of tubes according to the invention. In apparatus according to the invention the various layers of tubes are obtained in such a manner that all the axes of the tubes constituting a layer are contained within a cylindrical surface obtained in the manner shown in Figs. 1 and 2, the various layers having the same axis a and the same median plane 10.

Fig. 3 shows a section, through an axial plane, of the various cylindrical surfaces containing the layers of tubes constituting the nest of tubes according to the invention, the lines f indicating the track of these surfaces in the plane of the drawing. The sections 1, 2, 3 and 4 of Fig. 3 are those defined in Figs. 1 and 2.

Fig. 4 shows the arrangement of the tubes in a layer, according to the invention, the tubes being curved along an arc of a circle e defined in Fig. 2 and the terminal sections 1 and 4 being those defined in Figs. 1 and 2.

The method of construction of the nests of tubes according to the invention, may adapt itself to apparatus of very diverse dimensions, by reason of the freedom of selection which exists for the respective positionings of the sections 1, 2, 3, 4 and 10 and of the points 5 and 6, defined in Fig. 2. In particular, it is possible to obtain a nest of tubes in which the straight cylindrical portion comprised between the sections 2 and 3 is of zero value.

This last particular case may be obtained in the following two ways.

In the first way, the tubes having only a slight or zero curvature and each layer of tubes then has the shape of a hyperboloid of revolution, as shown in Fig. 6 in which the lines h represent the axes of the tubes forming a layer. In the second way, all the tubes forming the layer have a determined curvature and their axes are located in axial planes of the nest. Fig. 5 shows a view of such a layer of tubes, the lines g indicating the axes of the tubes forming this layer. 60

Other constructions of nests of tubes, according to the invention, can be obtained by juxtaposition of the partial elements, taken from the constructions above described. For example, it is possible to arrange the curved tubes in the arc of a circle in such a manner that their axes g are contained in one plane, as shown in Fig. 5, and a number of planes of tubes of this type may be juxtaposed in such a manner as to obtain a nest of tubes of arbitrary section varying arbitrarily. 70

The nest of tubes, according to the invention, obtained as above described, are secured in a known manner by swaging or by ramming in tubular plates. The tubular plates are more frequently plane but they may be arched.

In the case of heat exchangers with a nest of tubes which are to resist a high pressure, the nests of tubes, according to the invention, lend themselves particularly well to the construction of arched tube sheets, as the surface of these arched tube sheets may be substantially rectangular to the axes of the tubes, as indicated diagrammatically in Fig. 7, in which the lines i indicate the axes of the tubes and j indicates an arched tube sheet.

Fig. 8 shows, descriptively and not in any way in a limiting sense, an improved heat exchanger according to the invention. The lines l and the tubular plates define the position of the nest of tubes according to the invention, of which a tube k is shown. The casing n consists of a straight central cylindrical section and two end truncated sections into which the admission and outflow of fluid in circulation to the outside of the tubes takes place through the tubular members p and q . The fluid circulating in the interior of the tubes is guided by the tubular members r and s bolted in a known manner to the plane tubular plates m . The axis a of the apparatus is also the axis of the nest of tubes according to the invention. The detail of the arrangement of the tubes in the respective sections A—A and B—B of Fig. 8 shows that the cross sectional passage of fluid outside the tubes of the nest is appreciably greater in the inlet and outlet sections of this fluid than in the central cylindrical section.

What I claim is:

A heat exchanger comprising in combination 40 a pair of end plates, a series of tubes extending in longitudinally adjacent relationship and mounted between said end plates to form a bundle body having a generally cylindrical central portion of substantial length and divergent end portions, the center line of each of said tubes constituting an arc of a circle throughout its length facing concavely inwardly toward the central longitudinal axis of said bundle body, said tube center lines being each disposed in planes 45 forming equal acute angles with said central axis.
